STOKER

Joseph S. Bennett, Merion, Pa., assignor to American Engineering Company, Philadelphia, Pa., a corporation of Pennsylvania

Application December 31, 1937, Serial No. 182,763

9 Claims. (Cl. 122—4)

This invention relates to stokers, and more particularly to stokers of the fluid cooled type.

One object of the present invention is to provide a generally improved stoker of the fluid cooled type.

Another object is to provide improved tuyère constructions for stokers of the stated character which not only effectively distribute air for combustion in the fuel bed, but which are so disposed as to be effectively cooled by fluid cooling means, thereby insuring longevity of service.

Other and further objects will become apparent as the description of the invention progresses.

Of the drawings:

Fig. 1 is a longitudinal sectional view taken through one of the retorts of a stoker of the inclined grate, multiple retort, underfeed type, showing the fluid cooling system associated therewith.

Fig. 2 is a sectional view of one of the stoker tuyère rows, taken substantially along line 2—2 of Fig. 1.

Fig. 3 is a perspective view of one of the tuyère blocks secured to one of the tubes shown in Fig. 2.

Fig. 4 is a perspective view of the tuyère block shown in Fig. 3 in inverted position.

Fig. 5 is a perspective view of one of the tuyère blocks secured to the other of the tubes shown in Fig. 2.

Fig. 6 is a perspective view of the tuyère block shown in Fig. 5 in inverted position.

Fig. 7 is a fragmentary side view of a tuyère assembly of an alternative construction, parts of which are broken away to show the structure of the interior thereof, and of which parts are shown in section.

Fig. 8 is a sectional view taken substantially along line 8—8 of Fig. 7.

Fig. 9 is a perspective view of one of the tuyère blocks disposed between the tubes shown in Fig. 8, a portion of the end of which being broken away to show one of the air passages provided therein.

Figs. 10 and 11 are perspective views of the tuyère blocks disposed at the sides of the tubes shown in Fig. 8.

Fig. 12 is a fragmentary side view of another embodiment of the present invention, with parts broken away to show the construction of the interior thereof and with certain parts shown in section.

Fig. 13 is a sectional view taken substantially along line 13—13 of Fig. 12.

Fig. 14 is a longitudinal sectional view of a

further embodiment of the present invention taken substantially along line 14—14 of Fig. 15.

Fig. 15 is a transverse sectional view taken substantially along line 15—15 of Fig. 14.

Fig. 16 is a transverse sectional view showing a still further embodiment of the present invention, and

Fig. 17 is a side view partly in section and with certain parts removed to show the structure of the tuyère blocks, said view being taken substantially along line 17—17 of Fig. 16.

Referring to the drawings, the numeral 1 indicates a stoker of the inclined grates, multiple retort, underfeed type, consisting of alternately disposed retorts 2, and tuyère rows 3. Fuel from hoppers 4, disposed exteriorly of the front wall 5 of the furnace, is fed to the retorts by feeding rams 6, driven by any suitable power mechanism 7. Fuel is fed along each retort by a series of pushers 8 to a dead plate 9 disposed at the lower end thereof from which it is fed into an ash pocket 10 disposed at the rearmost end of the stoker. The pushers 8 are reciprocated by any suitable link and lever mechanism indicated generally at 11, and operatively connected to the power mechanism 7.

The sides of the retorts are bounded by substantially vertical walls which consist of longitudinally extending side plates 12 and 13, Figs. 30 1 and 2, and a series of side tuyère plates 14 and 15, secured respectively to side plates 12 and 13. Mounted respectively on the side tuyère plates 14 and 15 are tuyère members 16 and 17, which, as shown in Fig. 2, are provided with semi-circular recesses 18 and 19 respectively, for receiving fluid conducting tubes 20 and 21. The tubes 20 and 21 of each tuyère row 3 extend downwardly over the entire length thereof, and then are bent downwardly and forwardly, as shown at 22, and form a portion of the front wall of ash pocket 10. The lower ends of these tubes terminate in a header 23. The front end of tubes 20 and 21 are bent upwardly, as shown at 24, and extend vertically in close contact with the interior of front wall 5, and terminate at their upper ends in a boiler, not shown. Also extending upwardly from header 23 and lying between each pair of tubes 20 and 21, are one or more tubes 25. These tubes extend in substantially parallel relation with the lower portions of tubes 20 and 21, and also form a portion of the front wall of ash pocket 10 until reaching the upper end thereof, when they are bent forwardly so as to extend beneath and in intimate contact with dead plates 9. The forward ends

of tubes 25 then terminate in a header 26 disposed beneath the stoker. Header 23 is connected to the boiler by downtake connection 27, while header 26 is connected to the boiler by an uptake connection 28. Draft air is supplied to the furnace from a plenum chamber 29 disposed beneath the stoker, which is supplied with air under pressure by any suitable fan or blower mechanism (not shown) through a passage 30. The lower and rearwardly disposed end of the stoker receives air from a sub-plenum chamber 31, which communicates with chamber 29 through an opening 32, the size of the latter of which may be regulated by means of a damper 33.

Each side tuyère plate 14 is provided with an apertured flange 34 through which bolts 35 extend, and a shoulder 36 which rests upon the upper edge of side plate 12. Thus, to secure a side tuyère plate in position it is only necessary to align the apertures in flange 34 thereof with tapped openings in plate 12, and to then secure the plate in position. Each tuyère plate 15 is likewise provided with an apertured flange 37, and a longitudinally extending shoulder 38 which rests upon the upper edge of side plate 13. Bolts 39 are provided to rigidly secure plate 15 to plate 13.

The upper end of tuyère plate 14 is provided with a longitudinally extending projection 40 which interlocks with a groove 41 provided in the laterally extending portion 42 of tuyère member 16. Tuyère member 16 is drawn into intimate contact with tube 20 by means of a pair of bolts 43, welded or otherwise secured to the under side of the tube and arranged in spaced relation therealong. These bolts are provided with screw threads at their lower ends and are adapted to extend through apertures 44 provided near the ends of tuyère member 16, as shown more particularly in Figs. 3 and 4, and nuts 45 may then draw the tuyère member into contact with the tube. The under side of each tuyère member 16 has also provided therein a longitudinally extending slot 46, which forms an inlet passage for draft air. This slot communicates with a series of grooves 47 provided around one side of the semi-circular portion 18 of each tuyère member 16. Thus, when a tuyère member 16 is drawn into intimate contact with tube 20, contact is made only at spaced points therealong, the grooves provided in the semi-circular surface thereof providing a series of passages through which draft air may pass into the fuel bed. The laterally extending portion 42 of each tuyère block 16 has also provided therein a series of passages 48, through which draft air may enter the fuel bed.

The tuyère members 17 are generally similar in construction to tuyère members 16 and are shown more particularly in Figs. 5 and 6. This construction also has a laterally extending portion 49 provided with a longitudinally extending groove 50 at the lower end thereof which seats over the longitudinally extending projection 51 provided at the upper end of side tuyère plates 15. Tuyère members 17 are also secured to tube 21 by means of bolts 52, secured to tube 21 by welding or by any other suitable method of fastening. Bolts 52 are adapted to extend through apertures 53 provided near the ends of tuyère member 17 and nuts 54 engaging the lower ends of these bolts draw the tuyère member into intimate contact with tube 21. Each tuyère member 17 is also provided with a longitudinally

extending slot 55 at the lower side thereof through which draft air may pass. This slot communicates with a series of grooves 56 provided around one side of the semi-circular portion 19 and through which draft air passes to the fuel bed when the tuyère member 17 is assembled on tube 21. The laterally extending portion 49 of each tuyère member 17 is also provided with a series of passages 57 through which draft air may also pass into the fuel bed. Draft air also enters the fuel bed through passages 58 and 59 provided respectively in side tuyère members 14 and 15.

Referring to Fig. 2, it will be noted that when the tuyère members 16 and 17 are assembled on tubes 20 and 21 respectively, a space 60 is provided between the inner ends thereof through which draft air may also enter the fuel bed. It will be noted that the inner side of the tuyère members 16 extend slightly higher than the corresponding side of tuyère members 17, and that the inner ends of tuyère members 16 are each provided with a laterally extending lip 61 which overlaps a portion of the upper inner side of the adjacent tuyère member 17. By this construction a sufficient quantity of air passes into the fuel bed to effect complete combustion of the fuel and at the same time a partial seal is formed against the passage of siftings into the chamber beneath the stoker.

To prevent any possible distortion of the tubes 20 and 21 and the tuyère members secured thereto, securing bars 62 are provided. These bars are provided with apertures 63 near each end thereof in alignment with studs 43 and 52. These bars are assembled in position by simply moving the same vertically after aligning the apertures 63 with studs 43 and 52, and are held in position by the nuts 45 and 54, as shown in Fig. 2.

Figs. 7 to 11 inclusive, show a modified construction comprising intermediate tuyère members 64 and side tuyère members 65 and 66. As shown more particularly in Figs. 8 and 9, each intermediate tuyère member 64 is of angular construction having longitudinally extending arcuate surfaces 67 and 68 which are adapted to engage the inner surfaces of a pair of fluid conducting tubes 69 and 70, respectively. The upper surface 71 of tuyère member 64 is disposed slightly above the axes of tubes 69 and 70, and is provided with a series of steps 72. A series of air passages 73 is provided in the upper surface 71 of each tuyère member 64. Tuyère members 64 are held in intimate contact with tubes 69 and 70 by means of stud bolts 74 and 75, depending from the lower sides of tubes 69 and 70 respectively. Retaining bars 76 are also secured to bolts 74 and 75, and are held in position together with tuyère members 64 by means of nuts 77 and 78, engaging the lower threaded ends of said bolts.

Each tuyère member 65 comprises a vertical portion 80 terminating at its upper end in an offset arcuate portion 81, the latter of which engages the outer side of tube 69. The ends of arcuate portion 81 terminate in a pair of extended arcuate portions 82 and 83, each of which having an aperture 84 provided therein. These apertures are adapted to receive studs 85 welded or otherwise secured to tube 69 to prevent lateral movement of tuyère members 65. These studs also act as guides to insure proper contact between tube 69 and arcuate portion 81 during assembly of tuyère members 65 in position. The lower edge 86 of each tuyère member 65 is slightly inclined and engages the correspond-

ingly inclined upper surface of a wedge member 87, the lower surface of which rests upon an inwardly extending flange 88 of the side plate 89 of the tuyère chamber. A bolt 90, secured at one end near the upper end of side plate 89, loosely receives wedge 87. The wedge 87 is actuated toward side plate 89 by a nut 91 and washer 92 engaging the threaded inner end of bolt 90. Upon movement of wedge 87 in this manner tuyère member 65 is moved vertically into engagement with tube 69. To assemble a tuyère member 65 in position, it is first moved vertically toward tube 69 after apertures 84 have been brought into alignment with studs 85. Wedge 87 is then actuated by nut 91 to further actuate tuyère member 65 to bring the same into intimate contact with tube 69. As shown more particularly in Fig. 10, a series of grooves 93 are provided in arcuate portion 81 between the end portions 82 and 83. These grooves form passages for draft air adjacent the tube 69. As shown in Figs. 7 and 11, a series of passages 94 is also provided at the sides of vertical portion 80 of each tuyère member 65 through which draft air may also enter the fuel bed.

Each tuyère member 66 is identical in construction with tuyère member 65. Accordingly, a detailed description thereof is unnecessary. Upon reference to Fig. 8, however, it will be noted that the tuyère members 66 are secured to tube 70 by means of studs 95, and the bolt and wedge members 96 and 97, respectively.

Figs. 12 and 13 show a further modification of the present invention. This construction also comprises intermediate tuyère members 100 and side tuyère members 101 and 102. Each tuyère member 100 is provided with a pair of arcuate surfaces 103 and 104 which engage the upper inner sides of fluid conducting tubes 105 and 106 respectively. As shown in Fig. 12, each tuyère member 100 has provided therein a series of air passages 107, through which draft air may pass into the fuel bed. The ends of each tuyère member 100 are provided with enlarged portions 108 and 109 which have provided therein open ended recesses 110 and 111 respectively, for receiving securing bolts 112 and 113.

The tubes 105 and 106 extend lengthwise of the tuyère chamber and rest upon the concave portions 114 and 115 of supporting brackets 116. The lower ends of brackets 116 rest upon inwardly extending flanges 117 and 118 respectively of side plates 119 and 120. Locking pins 121 and 122 extending through flanges 117 and 118 respectively, secure the brackets 116 against lateral movement. Thus, to assemble the tuyère blocks 100 in position on tubes 105 and 106, it is only necessary to place them end to end along the length of said tubes, and to secure the abutting ends of pairs of tuyère blocks 100 in position in intimate contact with the tubes by means of nuts 125 engaging the upper threaded ends of bolts 112 and 113. It will be noted that slots 126 are provided at the ends of each tuyère block 100, which receive the shanks of bolts 112 or 113 so that the tuyère blocks may be moved into abutting relation with the next tuyère block of the series. Bolts 112 and 113 may be secured to the supporting brackets 116 by a pair of lock nuts 123, as shown in Figs. 12 and 13.

Each end tuyère block 101 comprises a substantially vertical portion 127 which rests upon the upper edge of side plate 119. The upper right hand end (Fig. 13) of portion 127 terminates in an arcuate portion 128 which engages

the left hand side of tube 105. A bolt receiving recess 129 is provided at each end of tuyère member 101 consisting of a reduced portion 130 for receiving the shank of a bolt 131, and an enlarged portion 132 for receiving a locking nut 133. Vertical portion 127 has also provided therein a series of passages 134 through which draft air may pass into the fuel bed. These passages may diverge toward the discharge end thereof to reduce the velocity of the air as it approaches the discharge end. To assemble the tuyère blocks 101 on the stoker they are simply placed in abutting relation, as shown in Figs. 1 and 2, and the bolts 131 are then passed through apertures provided in brackets 116, and the recesses 129. The lock nuts 133 then draw the blocks into intimate contact with tube 105.

Tuyère block 102 is similar in construction to tuyère block 101, and also comprises a vertical portion 134 which rests upon the upper edge of side plate 120 and an arcuate portion 135 which engages the right hand side of tube 106. Lock bolts 136 are provided to secure the blocks 102 to brackets 116 and in intimate contact with tube 106. Tuyère blocks 101 and 102 are respectively provided with longitudinally extending lips 137 and 138 to facilitate the assembly of said blocks on the stoker.

Figs. 14 and 15 disclose a still further modification of the present invention. This construction also consists of a series of intermediate tuyère blocks 140 and a pair of end tuyère blocks 141 and 142.

Each intermediate tuyère block 140 is held in position by an individual clamp block 143, thus affording a somewhat simplified form of securing means. As shown in Figs. 14 and 15, each tuyère block 140 is provided with arcuate surfaces 144 and 145 which respectively engage the inner sides of a pair of fluid conducting tubes 146 and 147. Depending from the lower side of each tuyère block 140 is a tongue 148, the upper surface 149 of which being inclined and receives the inclined surface 150 of the tongue 151 of clamp block 143. Each clamp block 143 is provided with arcuate side surfaces 152 and 153 which in assembly engage the lower inner sides of tubes 146 and 147 respectively. Thus, to secure a block 140 in intimate contact with the tubes 146 and 147, the retaining block 143 is moved longitudinally therealong until the tongues 148 and 151 interlock. To effect a tight joint between block 140 and tubes 146 and 147, an impact may be given to the clamp block 143 to wedge block 140 tightly into engagement with the said tubes. Series of grooves 154 are provided in the arcuate surfaces 144 and 145 of each tuyère block 140. These grooves form a series of passages between blocks 140 and tubes 146 and 147, through which draft air may pass to the fuel bed.

Blocks 141 and 142 are similar in construction to blocks 65 and 66, shown in Fig. 8, and therefore need not be described in detail. In this construction also wedges 155 and 156 are employed to urge blocks 141 and 142 respectively, into intimate contact with tubes 146 and 147. Studs 157 and 158 engage in apertures provided in blocks 141 and 142 to prevent lateral displacement of the blocks, as well as to guide them in their movement toward the tubes.

Figs. 16 and 17 show a still further modification of the present invention. In this construction tuyère blocks 160 and 161 of the toggle type are employed intermediate the tubes 162 and 163, while end tuyère blocks 164 and 165 are disposed

between tubes 162 and 163 respectively, and the corresponding side plates of the tuyère chamber. Tuyère blocks 160 and 161 are provided with arcuate surfaces 166 and 167 which respectively engage the inner surfaces of tubes 162 and 163. Block 160 is provided with a longitudinally extending projection 168, which engages in a correspondingly shaped recess 169 provided near the upper end of block 161. The lower ends of blocks 160 and 161 are provided with extensions 170 and 171 having aligned apertures provided therein for receiving the ends of an extensible bolt 172, having an operating nut 173 provided thereon. Thus, to urge blocks 160 and 161 into intimate contact with tubes 162 and 163, bolt 172 is simply extended by operation of nut 173, whereby the blocks pivot at the joint made between projection 168 and recess 169, thereby bringing the arcuate surfaces 166 and 167 respectively thereof into intimate contact with tubes 162 and 163. The arcuate surfaces 166 and 167 of blocks 160 and 161 are provided with a series of grooves 174 which, when the blocks are assembled in position on the tubes, form a series of passages through which draft air may enter the fuel bed. Passages may also be formed in tuyère block 161, as shown at 175, adjacent the joint between projection 168 and groove 169 to permit additional air to enter the fuel bed if it is so desired. To prevent distortion of tubes 162 and 163 securing bars 176 are provided. These bars are secured in any suitable manner to bolts 177 and 178, rigidly secured to tubes 162 and 163 respectively.

The end tuyère blocks 164 and 165 are similar in construction to the tuyère blocks shown in Fig. 8, and accordingly a detailed description thereof is unnecessary. In this construction it will be noted that wedges 179 are employed to urge the blocks into intimate contact with the tubes. Studs 180 and 181 secured to the tubes are also provided to prevent lateral movement of the end blocks 164 and 165, and also to assist in guiding the blocks in their movement into contact with the tubes.

From the foregoing description of the various embodiments of the present invention it is seen that simplified, as well as highly efficient constructions have been provided. Each tuyère construction is made up of a pair of tubes and different forms of tuyère block constructions mounted on said tubes in such a manner as to expose a portion of the surface thereof to the heat of the furnace. These tuyère blocks are both effectively cooled by contact with the fluid conducting tubes, as well as by the draft air passing therethrough, and as a result longevity of service is assured even under the most severe conditions of operation. These novel arrangements of tuyère blocks are also so constructed as to make it possible to renew them if necessary, without disturbing adjacent parts.

While the embodiments herein shown and described are admirably adapted to fulfill the objects primarily stated, it is to be understood that it is not intended to limit the invention to these embodiments since it may be embodied in other forms, all coming within the scope of claims which follow.

What is claimed is:

1. A furnace stoker, comprising alternately disposed retorts and tuyère rows, each of said tuyère rows consisting of a pair of spaced side walls, a tuyère assembly mounted on said side walls, said tuyère assembly consisting of a pair of longitudinally extending tubes, a row of

tuyère members secured beneath each of said tubes, lateral extensions on said tuyère members, coacting means on said tuyère members and tubes for holding said tuyère members in position and interlocking means on said lateral extensions and said side walls for supporting, as well as preventing lateral distortion of said tubes and tuyère members.

2. A furnace stoker, comprising alternately disposed retorts and tuyère rows, each of said tuyère rows consisting of a pair of spaced side walls, a tuyère assembly mounted on said side walls, said tuyère assembly comprising a pair of longitudinally extending tubes, a row of tuyère members secured beneath each of said tubes, each of said tuyère members having a longitudinally extending inlet passage, and a series of grooves communicating with said inlet passage, said grooves lying adjacent said tubes when the tuyère members are assembled thereon, thereby forming a series of passages for draft air, a lateral extension provided on each of said tuyère members for supporting the same in position, and means for drawing said tuyère members into intimate contact with said tubes.

3. A furnace stoker, comprising alternately disposed retorts and tuyère rows, each of said tuyère rows consisting of a pair of spaced side walls, a tuyère assembly mounted on said side walls, said tuyère assembly comprising a pair of longitudinally extending tubes, stud bolts secured to the lower sides of said tubes in spaced relation theralong, a row of tuyère members disposed beneath each of said tubes and secured to the latter by said stud bolts, lateral extensions provided on said tuyère members, side tuyère plates secured to each of said side walls, interlocking means on said lateral extensions and side tuyère plates, retaining means secured to said stud bolts to prevent distortion of said tubes, and each of said tuyère members having a series of passages provided therein through which draft air may pass.

4. A furnace stoker, comprising alternately disposed retorts and tuyère rows, each of said tuyère rows consisting of a pair of spaced side walls, a tuyère assembly mounted on said side walls, said tuyère assembly comprising a pair of longitudinally extending tubes, a row of tuyère members secured beneath each of said tubes, lateral extensions provided on said tuyère members for supporting said tuyère members and tubes in position on said side walls, the inner surface of one row of tuyère members being spaced from the inner surface of the adjoining row of tuyère members thereby providing a passage for draft air, and a lateral projection extending from each of the tuyère members of one of said rows and overlying the upper surface of the tuyère members of the adjacent row for preventing fuel siftings from passing between said rows of tuyère members.

5. A furnace stoker comprising alternately disposed retorts and tuyère rows, each of said tuyère rows consisting of a pair of spaced walls, a tuyère assembly mounted on said walls, said tuyère assembly comprising a pair of longitudinally extending tubes, a row of intermediate tuyère members disposed between said tubes, said tuyère members having an arcuate face at each side thereof conforming with the curvature of said tubes, means for urging said tuyère members into contact with said tubes, a row of said tuyère members disposed between one of said tubes and one of said side walls, a second row of said tuyère

members disposed between the other of said tubes and the other of said side walls, and adjustable means for urging said side tuyère members into intimate contact with said tubes.

6. A furnace stoker comprising alternately disposed retorts and tuyère rows, each of said tuyère rows consisting of a pair of spaced walls, a tuyère assembly mounted on said walls, said tuyère assembly comprising a pair of longitudinally extending tubes, a row of intermediate tuyère members disposed between said tubes, each of said intermediate tuyère members having a pair of concave faces adapted to engage the inner surfaces of said tubes, stud bolts depending from said tubes for securing said intermediate tuyère members in intimate contact with said tubes, a row of side tuyère members disposed between one of said tubes and one of said side walls, each of said side members having an arcuate face adapted to engage the outer side of said tube, means for urging said side tuyère members into intimate contact with said tube, and means depending from said tube interlocking with said side tuyère members for preventing lateral displacement of the latter, a second row of side tuyère members disposed between the other of said tubes and the other of said side walls, each of said last mentioned side tuyère members having an arcuate face provided thereon adapted to engage the outer side of said last mentioned tuyère members into intimate contact with said last mentioned tube, and each of said tuyère members having passages provided therein through which draft air may pass.

7. A furnace stoker, comprising alternately disposed retorts and tuyère rows, each of said tuyère rows consisting of a pair of spaced walls, a tuyère assembly mounted on said walls, said tuyère assembly comprising a pair of longitudinally extending tubes, a row of intermediate tuyère members disposed between said tubes, each of said intermediate tuyère members having a pair of concave faces adapted to engage the inner surfaces of said tubes, stud bolts depending from said tubes for securing said intermediate tuyère members in intimate contact with said tubes, a row of side tuyère members

disposed between one of said tubes and one of said side walls, each of said side members having an arcuate face adapted to engage the outer side of said tube, means for urging said side tuyère members into intimate contact with said tube, and means depending from said tube interlocking with said side tuyère members for preventing lateral displacement of the latter, a second row of side tuyère members disposed between the other of said tubes and the other of said side walls, each of said last mentioned side tuyère members having an arcuate face provided thereon adapted to engage the outer side of said last mentioned tube, means for urging said last mentioned tuyère members into intimate contact with said last mentioned tube, each of said tuyère members having passages provided therein through which draft air may pass, and retainer bars secured to said first mentioned studs for preventing lateral displacement of said tubes.

8. A tuyère block adapted for assembly on a tube of a fluid cooled stoker, said tuyère block comprising an elongated body structure having an arcuate tube receiving portion, and a laterally extending supporting portion, said arcuate portion having a series of grooves provided therein forming a series of air passages when the tuyère block is assembled on said tube, and said supporting portion having a series of passages through which additional draft air may pass.

9. A side tuyère member adapted for assembly on a stoker of the fluid cooled type, said tuyère member comprising an elongated body structure having a transversely inclined lower edge adapted to engage operating means, and an arcuate tube receiving portion at the other end thereof, said arcuate portion having a series of grooves provided therein forming passages for draft air when said tuyère member is assembled on the stoker and apertures for receiving projections provided on the tube to prevent lateral movement of said tuyère member, and said body structure having a series of air passages provided at the side thereof through which additional draft air may pass.

JOSEPH S. BENNETT.
